UNITED STATES PATENT OFFICE.

JOHN P. NELSON, OF SAN ANTONIO, TEXAS.

SCRAPER FOR ASPHALT-COOKING DRUMS.

SPECIFICATION forming part of Letters Patent No. 705,954, dated July 29, 1902.

Application filed April 21, 1902. Serial No. 104,005. (No model.)

To all whom it may concern:

Be it known that I, JOHN P. NELSON, a citizen of the United States, residing at San Antonio, in the county of Bexar and State of Texas, have invented new and useful Improvements in Scrapers for Asphalt-Cooking Drums, of which the following is a specification.

This invention relates to a scraper for asphalt-cooking drums; and the objects of the invention are to provide a simple and effective device of this character which is adapted to prevent the heated asphalt from sticking or adhering to the inner surface of said drums, and thus clogging the same.

In the preparation of the natural rock asphalt for the paving of public streets such asphalt after having been crushed or pulverized is passed through what is commonly known as a "cooking-drum," which is maintained in a heated condition and continuously revolved while the asphalt is being passed through the same. After the asphalt has become heated to a certain extent it has a tendency to cling or adhere to the inner surface of said drum, and thus clog the same. By virtue, however, of my improved scraper the adherence of the heated asphalt to the drum is prevented. I employ in combination with such a drum a scraper having a straight edge adapted to bear against the inner surface of said drum, a shaft carrying said scraper and extending through and beyond the drum, and a weighted arm carried by the shaft outside the drum, and in the present case the bearings for the shaft are horizontally adjustable, so that the scraper can be moved nearer to or farther from the drum, and I prefer to employ two of such arms in order to secure a proper contact of the working edge of the scraper with the inner surface of the drum, and the weights thereof are generally made adjustable, so that a greater or less leverage can be exerted upon the scraper. As the arm or arms referred to are entirely outside of the drum, the weights thereof can be adjusted at any time, even while the drum is in motion. Beside this the scraper can be moved out of its operative position by simply manipulating one or the other of said arms, it being understood that they are readily accessible for this purpose.

The invention is clearly represented in the accompanying drawings, forming a part of this specification, and in which—

Figure 1 is a side elevation of an asphalt-cooking drum and my improved scraper. Fig. 2 is a plan view of the scraper, and Fig. 3 is a perspective sectional detail of a part of the scraper.

Like characters refer to like parts in all the figures.

In Fig. 1 I have shown at 5 an asphalt-cooking drum which is of ordinary construction and which, as usual, is mounted at a slight incline toward the open end thereof, so that the hot asphalt travels toward such end. The said drum is continuously rotated in the direction of the arrow by a suitable means (not shown) and is mounted upon the rollers 6 and 7, carried by suitable bearings upon the framework 8, the side bars 9 of which are adapted also to sustain the scraper mechanism.

The scraper, which extends entirely through the drum, includes in its construction a plate 10, which has a curved lip 11, having a straight edge 12, adapted to bear in contact with the inner surface of the drum 5, as shown in Fig. 1. Said plate 10 may be made of steel or any other suitable material. The scraper-plate 10 is carried by a shaft 13, the two parts being suitably secured together—as, for example, by means of the U-bolts 14, adapted to straddle the shaft 13 and the branches of which extend through the scraper-plate and are provided upon what may be considered the under ends thereof with the usual holding-nuts.

It will be understood that the shaft 13 extends entirely through the drum 5 and beyond the ends of said drum, said shaft being supported by bearings 15, supported upon the side bars 9 of the framework. Bolts, as 16, extend vertically through the bearings 15 and side bars 9 and serve as a suitable means for holding the two parts in engagement, said bolts projecting through longitudinal slots in the bearings, whereby the latter can be adjusted horizontally in order to move the scraper-plate nearer to or farther from the inner surface of the drum in order to thereby adjust the angle of the scraper-plate with respect to said inner surface.

The shaft 13 carries at its opposite ends the arms 17, suitably secured to said shaft and provided with sliding weights 18, held in their adjusted positions by set-screws 19.

5 Referring to Fig. 1, it will be seen that the arms 17 extend upward toward the left, so that the weights 18 thereof are adapted to force the working edge of the scraper-plate into firm contact with the inner surface of the 10 drum, and by adjusting one or both of the weights nearer to or farther from the axis of the rock-shaft 13 the pressure of the scraper-plate against the drum can be regulated. It is apparent, of course, that one of the arms 15 17 may be omitted, although I prefer to employ two of them in order to secure a more uniform contact of the scraper-plate with the drum. It will be seen that both of the arms are entirely outside of the drum, so that the 20 weights 18 can be adjusted even when the drum is in motion. Beside this the said arms serve as suitable hand-levers, and either one of them can be grasped to carry the working edge of the scraper-plate out of engagement 25 with the drum. By virtue also of the disposition of the arms I may make them of considerable length, so that I can obtain a wide range of adjustment of the weights 18. As the drum rotates in the direction of the arrow 30 the hot asphalt will travel slowly toward the open end thereof, as is the custom, and any of the asphalt that sticks to the inner surface of said drum will when it comes in contact

with the straight and sharp edge of the scraper-plate be dislodged and will follow the 35 curved portion 11 of the scraper-plate and will then fall back to the bottom of the drum.

The invention is not limited to the precise construction hereinbefore described, for various changes may be made within the scope 40 of the claims.

Having described the invention, what I claim is—

1. The combination of an asphalt-cooking drum, a scraper-plate having a straight edge 45 adapted to bear against the inner surface of said drum, a shaft carrying said scraper-plate and extending beyond the drum, a weighted arm carried by the shaft outside the drum, and adjustable bearings for said shaft. 50

2. The combination of an asphalt-cooking drum, a scraper-plate having a straight edge adapted to bear against the inner surface of said drum, a shaft carrying said scraper-plate and extending through and beyond the 55 drum, weighted arms carried by the shaft outside the drum, and the weights thereof being adjustable and horizontally-adjustable bearings for said shaft.

In testimony whereof I have hereunto set 60 my hand in presence of two subscribing witnesses.

JOHN P. NELSON.
